COMBINATION SOAKER HOSE REEL AND FLEXIBLE ATTACHMENT

Richard R. Rohling, 861 Carl Ave.,
Anoka, Minn. 55303

Filed Oct. 28, 1975, Ser. No. 626,471

Term of patent 14 years

Int. Cl. D8—05

U.S. Cl. D8—221

Fig. 1

Fig. 2

Fig. 3

Fig. 4

FIG. 1 is a perspective view of a combination soaker hose reel and flexible attachment showing in dotted outline for purposes of illustration of use of a portion of a soaker hose attached thereto.

FIG. 2 is an end elevational view of the combination soaker hose reel and flexible attachment wherein the flexible adapter has been removed for purposes of illustration only.

FIG. 3 is a side elevational view of the combination soaker hose reel and flexible attachment with the flexible adapter in a loosely coiled configuration, and

FIG. 4 is the opposite side elevational view of FIG. 3 with the soaker hose adapter removed again for purposes of clarity in the drawings.

I claim:

The ornamental design for a combination soaker hose reel and flexible attachment, as shown and described.
